UNITED STATES PATENT OFFICE.

CHARLES LEWIS, OF DE QUINCY, LOUISIANA.

COMB.

Application filed June 5, 1922. Serial No. 566,100.

To all whom it may concern:

Be it known that I, CHARLES LEWIS, a citizen of the United States, residing at De Quincy, in the parish of Calcasieu and 5 State of Louisiana, have invented certain new and useful Improvements in a Comb, of which the following is a specification.

This invention relates to new and useful improvements in a comb.

10 One object of the invention is to provide a comb of the character described especially designed for combing tangled or curly hair, and may be also used for untangling and combing out wool or similar fibrous 15 material.

Another object of the invention is to provide a comb provided with fixed and movable teeth and having means for operating the movable teeth manually during the 20 combing process.

Another object of the invention is to provide a comb of the character described having fixed and movable teeth and equipped with means for locking said movable teeth 25 against movement if desired.

With the above and other objects in view the invention has particular relation to certain novel features of construction, use and arrangement of parts, an example of which 30 is given in this specification and illustrated in the accompanying drawings, wherein:—

Figure 1 shows a side view of one form of the comb.

Figure 2 shows an end view thereof.

35 Figure 3 shows an edge view of the comb showing the handle in section.

Figure 4 shows a sectional view thereof taken on the line 4—4 of Figure 3.

Figure 5 shows a side view of another 40 form of the comb partially broken away.

Figure 6 is a transverse sectional view thereof taken on the line 6—6 of Figure 5 and,

Figure 7 shows an edge view of this form 45 of the comb showing the handle in section.

In the drawings the numeral 1 designates the handle to one end of which there is riveted or otherwise secured the tooth support 2, which is formed with the fixed teeth 3 spaced apart therealong. Slidably mounted there is the tooth support 4 which carries the spaced teeth 5, conforming in contour to the shape, and coinciding with the teeth 3. The supports 2 and 4 are flat members which fit together and which are em-

braced by the back 6 formed of metal or other suitable material. The movable support 4 has oblong slots 7 through which the rivets 8 of the fixed support extend, the slots limiting the range of movement of the 60 movable support 4. The handle is hollow and threaded into the outer end thereof there is a plug 9. The movable support 4 has an extended shank 10 which fits into the handle and interposed between this 65 shank and the plug 9 there is a push spring 11 and pivotally mounted in the handle and working through the bearing 12 thereof there is a lever 13 whose outer end is formed with a flared extension 14. The inner end 70 of this lever works in a bearing 15 in the shank 10. While the comb is in use the outer end of the lever 14 may be depressed thus forcing the teeth apart and when said lever is released the pressure spring 11 will 75 force said teeth together and thus manipulating said handle, the teeth may be worked back and forth which will assist in separating and straightening the hair or other material to be combed.

In the form shown in Figures 5, 6 and 7 the stationary tooth support is formed of the side members 16, 16 which are spaced apart and has a suitable back as 17. Working between the side members 16 there is 85 a movable tooth support 18. These supports have the respective teeth 18 and 19 fixed thereto of similar contour and fitting against each other. In other respects the two forms of the comb are substantially 90 similar. If it is desired the movable teeth may be locked against movement either by the set screw 20 which is threaded through the handle against the shank 10 or by means of the clamp screw 21 which is fitted 95 through a slot 22 in the handle and threaded into said shank 10. These alternative forms of locking are shown in Figures 3 and 7 respectively.

What I claim is:—

1. A comb comprising, a tubular handle, a relatively stationary support fixed to the handle and having spaced teeth, a movable support shiftable longitudinally of the stationary support and having a shank 105 slideable within the tubular handle, said movable support having spaced teeth coacting with the first named spaced teeth, a coil spring within the tubular handle engaging the shank to move it forwardly so that the 110

movable set of teeth are in the open position, and a lever pivoted upon the handle and engaging the shank within said tubular handle, said lever having its outer end moved forwardly with relation to the handle to shift the movable teeth to the closed position in close proximity to the stationary teeth.

2. A comb comprising, a tubular handle,
10 a relatively stationary support fixed to the handle and having spaced teeth, a movable support slideable longitudinally of the stationary support and having a shank slideable within the tubular handle, said movable support having spaced teeth coacting
15 with the first named spaced teeth, a coil spring within the tubular handle, engaging

the shank to move it forwardly so that the movable set of teeth are in the open position, a lever pivoted upon the handle and engaging the shank within said tubular handle, said lever having its outer end projecting forwardly with relation to the handle, and a locking device carried by the handle to engage said shank and hold the same 20 against movement.

In testimony whereof I have signed my name to this specification in the presence of two subscribing witnesses.

CHARLES LEWIS.
